UNITED STATES PATENT OFFICE.

BROR MAX SCHAUMAN, OF ATLANTIC HIGHLANDS, NEW JERSEY, ASSIGNOR TO AN ASSOCIATION COMPRISING GRANDIN V. JOHNSON, OTTO GAUTSCHY, AND HARRY W. JOHNSON, ALL OF HIGHLANDS, NEW JERSEY; WILLIAM KOCH, OF LONG BRANCH, NEW JERSEY; AND BROR MAX SCHAUMAN, OF ATLANTIC HIGHLANDS, NEW JERSEY, ONE-FIFTH TO EACH MEMBER.

DAVIT.

Application filed August 3, 1922, Serial No. 579,369. Renewed November 17, 1926.

This invention relates to ship's davit contrivances for facilitating the lowering and raising of a ship's anchor without fouling the sides or injuring the deck of the vessel. 5 To carry out the invention the ship is provided with a carrier which supports the anchor in its raised position. Said carrier is provided with a swingable portion to which the anchor is attached, and the construction is such that when the carrier is in its outermost position said swingable portion swings clear of the vessel and hence permits the anchor to be lowered without engaging any part of the ship. The carrier 10 remains in its outermost position while the anchor is in lowered position, so that when the anchor is raised it rests first upon the swingable portion clear of the vessel, and said swingable portion is then rotated to its initial position upon the carrier and the latter drawn inwardly. 15

It is a further object of this invention to provide means whereby the anchor upon being raised will adjust itself in position 20 upon the swingable member.

Another object of this invention is to provide means whereby the anchor will be automatically locked in position upon the carrier, thus preventing slipping or rocking of the 25 anchor due to the motion of the vessel.

Other features and advantages will hereinafter appear.

In the accompanying drawings:

Figure 1 is a side view, partly sectioned, 30 showing my invention applied to a vessel, the anchor being in raised position and resting upon the carrier;

Figure 2 is a view similar to Figure 1, but with the anchor in position for lowering;

Figure 3 is a view similar to Figures 1 and 2, but with the anchor in position upon the swingable member just before the latter is drawn upon the carrier;

Figure 4 is a perspective view of the carrier and its support;

Figure 5 is a plan view of the carrier-support;

Figure 6 is a detail perspective view of the upper end of the movable member showing the means whereby the anchor is properly positioned upon the support;

Figures 7 and 8 are enlarged details showing how the upper end of the movable member operates to position the anchor properly with respect to the support;

Figures 9 and 10 are views of the lower end of the movable member showing additional means for properly positioning and supporting the anchor thereon.

Referring to the drawings, there is shown a portion of a vessel having a side 10 and a deck 11, the davit contrivance being shown applied to the deck. The vessel is provided with an anchor which may be of any ordinary type and has preferably a shank 12, a stock 13, a ring 14 at one end of the shank, and arms 15 at the other end of the shank, said arms being in a plane perpendicular to the plane of the shank and stock. For raising the anchor there is provided the usual cable 17 tied to the ring 14 at one end, and the other end of the cable being wound by any suitable mechanism, such as a winch. The anchor is lowered, of course, by releasing the cable so that the anchor can fall under its own weight.

It is desirable that when the anchor is raised or lowered it shall not foul the side of the vessel. For this purpose there must be provided means whereby the anchor may be carried from the deck of the vessel to a point beyond the side thereof before the anchor is allowed to fall, and means whereby the anchor may be fully raised and returned to the deck without engaging the vessel. To perform these functions there is provided a carrier 20 mounted for outward and inward movement, toward and away from the side of the vessel, preferably upon guide rods 21 which may be fixed in brackets 22 upon a base 23 attached to the deck of the vessel. The carrier may be moved by means of a cable or rope 25 and pulleys 26 and 27, which are mounted on the base 23 and carrier 20 respectively. The rope may be wound by any suitable means, as by a winch. In its outward position the carrier extends substantially to the side of the vessel, and for holding the anchor a considerable distance away from the side there is provided an anchor support 30 fixed to a bracket 28 which is pivotally mounted at 29 on the end

of an outwardly projecting arm 31 fixed upon the carrier. Said support is provided with a bent-off portion or arm 33, which, when the support 30 has swung about the 5 pivot 29, forms an outward extension considerably beyond the vessel, the anchor being suspended from the end of said arm 33 in position for lowering (see Fig. 2). The anchor may thus be lowered without danger 10 of its contacting with the vessel and avoiding any possibility of injury to the ship. The outer end of arm 33 may be provided with a pulley 34 over which the cable 17 operates.

15 When the anchor is to be raised, rope 17 is wound up, thus tending to draw carrier 20 inwardly since the rope 17 passes beneath a pulley 36 fixed to the carrier, the latter, however, being held in its outward 20 position because rope 25 is wound up. Until the anchor is fully drawn up to pulley 34, support 30 is held in the Figure 2 position substantially vertical, the weight of the anchor tending to rotate the support 25 about pivot 29 to keep said support in contact with the side of the vessel. When the anchor reaches the pulley 34, however, further pulling upon rope 17 will draw carrier 20, support 30 and the anchor inwardly 30 along guide rods 21 until the carrier reaches its innermost position where it may be held by fastening rope 17 against unwinding.

To lower the anchor, rope 25 is wound up to draw the carrier outwardly, rope 17 being 35 released sufficiently to permit said outward movement. When the carrier has reached its outermost position, further release of rope 17 will permit the anchor by its weight to rotate member 30 about pivot 29 to the 40 Figure 3 position. Still further release of rope 17 will permit the anchor to hang freely from the end of arm 33 some distance removed from the side of the vessel, from which position the anchor may be 45 freely lowered by further unwinding of rope 17. It will thus be apparent that the support 30 maintains the anchor out of contact with the ship at all times, releasing the anchor beyond the side of the vessel when it 50 is to be dropped, and taking it up again beyond the vessel when it is raised.

To enable the anchor while being raised to position itself properly upon the support 30, there may be provided adjacent one 55 side of the pulley 34 a cam surface 40 which tends to turn the ring 14 into the plane of the pulley 34, and hence the arms 15 of the anchor, which are in a plane perpendicular to the plane of the ring, will be located 60 substantially perpendicular to the plane of the ring. Positioned at the lower end of support 30 in a plane perpendicular to the plane of pulley 34, and hence parallel to the plane of arms 15, is a cross-bar 42 having 65 arm-supports 43. As the anchor-ring

reaches its Figure 8 position the arms 15 will be turned into a plane parallel to cross-bar 42, and further pulling upon rope 17 will tilt support 30 inwardly to the Figure 3 position, and arms 15 will come to rest upon cross-bar 42 and arm-supports 43. The action is thus self-adjusting. The arms 43 are adjustably mounted on the cross-bar 42 to accommodate anchor arms of various sizes, and the cross-bar 42 is adjustably mounted upon the member 30 to accommodate anchors having various sized shanks.

When the support 30 and the anchor are tilted inwardly against the carrier, and the latter has been pulled inwardly, the lower end of the support and anchor may rest upon a shelf 45 fixed to the carrier-supporting mechanism, and preferably to the outer bracket 22. To prevent rocking or slipping of the anchor upon the shelf due to movement of the boat, there may be provided upon the shelf hooks 47 which engage over the arms of the anchor.

I claim:

1. A ship's davit contrivance for facilitating the hoisting and lowering of an anchor without injury to the ship, said contrivance including a pivotally-mounted support for normally carrying said anchor upon said ship, said support being movable outwardly beyond the limits of said ship, said support when beyond the limits of the ship being swingable about its pivot to permit said anchor to be lowered without engaging the ship.

2. A ship's davit contrivance for facilitating the hoisting and lowering of an anchor without injury to the ship, said contrivance including a pivotally-mounted support for normally supporting said anchor upon said ship, said support being movable outwardly beyond the limits of said ship, said support when beyond the limits of said ship being swingable about its pivot to permit said anchor to be lowered without engaging the ship, and means whereby said anchor positions itself upon said support when raised.

3. In a ship's davit contrivance for facilitating the hoisting and lowering of an anchor without injury to the ship, said anchor having arms, a pivotally-mounted support for normally supporting said anchor upon said ship, said support having arms for normally supporting said anchor-arms, said support being movable outwardly beyond the limits of said ship, said support when beyond the limits of the ship being swingable about its pivot to permit said anchor to be lowered without engaging said ship, and means whereby said anchor-arms position themselves upon said supporting-arms when said anchor is raised.

4. In a ship's davit contrivance for facilitating the hoisting and lowering of an an-

5   anchor without injury to the ship, said anchor having a ring and having arms in a plane perpendicular to the plane of the ring, said anchor being operable by a cable attached
10   to said ring, a pivotally-mounted support for normally supporting said anchor upon said ship, said support having arms for normally supporting said anchor-arms, said support being movable outwardly beyond the limits of said ship, said support when beyond the limits of said ship being swingable about its pivot to permit said anchor to be lowered without engaging said ship, said support comprising a pulley over which said
15   cable operates, and a cam adjacent said pulley and substantially perpendicular to the plane of said supporting-arms, said cam engaging said ring when the anchor is raised to turn said ring into the plane of said cam
20   and said anchor-arms into the plane of said supporting-arms to enable said anchor-arms to position themselves upon said supporting-arms when the anchor is raised.

5. A ship's davit contrivance for facilitating the hoisting and lowering of an anchor without injury to the ship, said contrivance including a carrier mounted upon said ship for inward and outward movement, a support pivotally mounted upon said carrier and normally carrying said anchor, said support being swingable about its pivot beyond the limits of said ship when said carrier is moved outwardly to permit said anchor to be lowered without engaging said ship.

35 6. A ship's davit contrivance for facilitating the hoisting and lowering of an anchor without injury to the ship, said contrivance including a carrier mounted upon said ship for inward and outward movement, an outwardly projecting arm fixed to said carrier so that when said carrier is in its outward position said arm projects beyond the limits of said ship, a bracket pivotally secured to said arm, a support on said bracket and normally supporting said anchor, said support being swingable about the bracket pivot when said carrier is in its outward position to permit said anchor to be lowered without engaging said ship.

40

45

50 7. A ship's davit contrivance for facilitating the hoisting and lowering of an anchor without injury to the ship, said contrivance including a carrier mounted upon said ship for inward and outward movement, means
55 for moving said carrier outwardly and for holding it in outward position, a support pivotally mounted upon said carrier and normally carrying said anchor, said support being swingable about its pivot beyond the
60 limits of said ship when said carrier is moved outwardly, and means permitting the support to be swung about its pivot when the carrier is in outward position so that said anchor may be released off of the support
65 and lowered without engaging said ship.

8. A ship's davit contrivance for facilitating the hoisting and lowering of an anchor without injury to the ship, said contrivance including a carrier mounted upon said ship for inward and outward movement, means for moving said carrier outwardly and for holding it in its outward position, a support pivotally mounted upon said carrier and normally carrying said anchor, said support being swingable about its pivot beyond the limits of said ship when said carrier is moved outwardly, a cable connected to said anchor, said cable being released when said carrier is in outward position to permit said anchor to swing the support about its pivot so that said anchor may be released off of the support and lowered without engaging said ship.

9. A ship's davit contrivance for facilitating the hoisting and lowering of an anchor without injury to the ship, said contrivance including a carrier mounted upon said ship for inward and outward movement, means for moving said carrier outwardly and for holding it in its outward position, a support pivotally mounted upon said carrier and normally carrying said anchor, said support being swingable about its pivot beyond the limits of said ship when said carrier is moved outwardly, a cable connected to said anchor, said cable being released when said carrier is in outward position to permit said anchor to swing the support about its pivot so that said anchor may be released off of the support and lowered without engaging said ship, said cable, when wound up, raising said anchor upon the support, said cable, when further wound up, swinging said support and anchor inwardly and moving said carrier inwardly when the means for holding said carrier in outward position has been released.

10. A ship's davit contrivance for facilitating the hoisting and lowering of an anchor without injury to the ship, said contrivance including a carrier mounted upon said ship for inward and outward movement, means for moving said carrier outwardly and for holding it in its outward position, a support pivotally mounted upon said carrier and normally carrying said anchor, said support being swingable about its pivot beyond the limits of said ship when said carrier is moved outwardly, a cable connected to said anchor, said cable being released when said carrier is in outward position to permit said anchor to swing the support about its pivot so that said anchor may be released off of the support and lowered without engaging said ship, said cable, when wound up, raising said anchor upon the support, said cable, when further wound up, swinging said support and anchor inwardly, said cable being connected to said carrier so that further winding of the cable moves said carrier inwardly when

the means for holding said carrier in outward position has been released.

11. A ship's davit contrivance for facilitating the hoisting and lowering of an anchor without injury to the ship, said contrivance including a carrier, a guiding-support fixed to said ship and upon which said carrier operates for inward and outward movement, a support pivotally mounted upon said carrier and normally carrying said anchor in inward position, said support being swingable about its pivot beyond the limits of said ship when the carrier is in outward position to permit the anchor to be released off of the support and lowered without engaging the ship, said anchor when in inward position being supported in part upon said guiding-support, and means fixed to said guiding-support and engaging the anchor in its inward position for holding said anchor against movement.

12. A ship's davit contrivance for facilitating the hoisting and lowering of an anchor without injury to the ship, said contrivance including a carrier, a guiding-support fixed to said ship and upon which said carrier operates for inward and outward movement, a support pivotally mounted upon said carrier and normally carrying

15 said anchor in inward position, said support being swingable about its pivot beyond the limits of said ship when the carrier is in outward position to permit the anchor to be lowered without engaging the ship, said anchor when in inward position being supported in part upon said guiding-support, and catches on the guiding-support for holding said anchor 20 against movement upon said guiding-support.

13. A ship's davit contrivance for facilitating the hoisting and lowering of an anchor without injury to the ship, said contrivance including a carrier, a guiding-support fixed to said ship and upon which said carrier operates for inward and outward movement, a support pivotally mounted upon said carrier and normally supporting said anchor in inward position, said support being swingable about its pivot beyond the 25 limits of said ship when the carrier is in outward position to permit the anchor to be lowered without engaging the ship, said anchor when in inward position being supported in part upon said guiding-support, 30 said anchor having arms, and catches fixed to said guiding-support and engaging said anchor-arms in the inward position of the anchor to hold said anchor against movement.

the limits of said ship when the carrier is in outward position to permit the anchor to be released off of the support and lowered without engaging the ship, said anchor when in inward position being supported in part upon said guiding-support, and means fixed to said guiding-support and engaging the anchor in its inward position for holding said anchor against movement.

14. A ship's davit contrivance for facilitating the hoisting and lowering of an anchor without injury to the ship, said contrivance including a carrier, a guiding-support fixed to said ship and upon which said carrier operates for inward and outward movement, a support pivotally mounted upon said carrier and normally supporting said anchor in inward position, said support being swingable about its pivot beyond the 45 limits of said ship when the carrier is in outward position to permit the anchor to be lowered without engaging the ship, said anchor when in inward position being supported in part upon said guiding-support, 50 said anchor having arms, and catches fixed to said guiding-support and engaging said anchor-arms in the inward position of the anchor to hold said anchor against movement.

In testimony whereof I affix my signature.
BROR MAX SCHAUMAN.
